UNITED STATES PATENT OFFICE.

WILLIAM S. THOMAS, OF GRAND RAPIDS, MICHIGAN.

CANNING-FACTORY DEVICE.

No. 907,917.

Specification of Letters Patent.

Patented Dec. 29, 1908.

Application filed January 7, 1908. Serial No. 409,670.

To all whom it may concern:

Be it known that I, WILLIAM S. THOMAS, a citizen of the United States of America, residing at Grand Rapids, in the county of Kent and State of Michigan, have invented certain new and useful Improvements in Canning-Factory Devices; and I do hereby declare the following to be a full, clear, and exact description of the invention, such as will enable others skilled in the art to which it appertains to make and use the same.

My invention relates to improvements in canning factory devices, and its object is to provide a convenient means for conveying fruit to the operatives; carrying away the filled cans and conveying away the refuse; and also to provide the device with various new and useful features hereinafter more fully described and particularly pointed out in the claims.

My device consists essentially of the combination and arrangement of an extended table above which and parallel therewith is supported a run-way in one direction and traversing the middle of the table beneath the run-way in the opposite direction for the belt, a belt traversing the run-way, sinks or receptacles in the table, a trough below the table, a conveyer in the trough, means for operating the belt and conveyer, means for supplying water to each receptacle, and in various features of combination and arrangement, as will more fully appear by reference to the accompanying drawings, in which:

Figure 1. is a plan view of a device embodying my invention; Fig. 2, a side elevation of the same with parts broken away; Fig. 3. a transverse section of the same; and Fig. 4. an end elevation of the same.

Like numbers refer to like parts in all of the figures.

1 represents a table of any convenient length, extending horizontally above the table and at a distance therefrom is a run-way 2 traversed by the upper part of a belt 3, the lower part of the belt traversing the middle of the table directly beneath the run-way. At each end of the table are pulleys 4 and 6 engaging the belt, the pulley 4 being mounted on a driving shaft 5 rotated by any convenient motive power, the pulley 6 having its journals in bearings 7, horizontally adjustable in ways 8, by means of screws 9, to maintain proper tension on the belt 3. 10 55 are sinks or receptacles extending downward from openings in the table, one side of

said openings being adjacent to the edge of the lower part of the belt 3, each receptacle 10 being also provided with a drain pipe 11 adapted to discharge the contents thereof into a trough 13 located near the floor and beneath the table. Near each sink and close to the outer edge of the table are also smaller openings from which extend spouts 12 to discharge anything placed therein into 60 said trough. Within this trough is a sprocket chain 14 having transverse drag bars 15 at intervals thereon, the lower part of the said chain being adapted to traverse these bars along the bottom of the trough and to discharge the contents of the trough 70 at one end thereof. The upper part of the chain is carried upon idlers 23 arranged at intervals to support the chain at a distance above the bottom of the trough. 75

16 and 17 are sprocket wheels engaging said chain, one of which is driven by a chain 18 extending to a corresponding sprocket wheel 20 on the driving shaft 5 and engaging a sprocket wheel 19 on the shaft carrying the 80 wheel 14. A water pipe 21 extends beneath the platform 2 and is provided with a branch pipe opposite each sink inserted in which is a suitable cock or faucet 22 to supply water to each sink as occasion requires. 85

In operation the respective upper and lower parts of the belt 3 run in opposite directions, and upon the lower part at one end of the table is fed the fruit, or other material to be handled by the operatives stationed opposite the respective sinks. As the material comes opposite the various sinks, each operative takes off from the lower part of the belt so much as may be needed and the balance is passed on down the table and the residue is 90 removed at the other end if any remains on the belt. Each operative is supplied with cans, bottles, jars or other packages in which the material is placed and the same when filled is placed upon the upper part of the 100 belt, which carries the same back to the end of the table where the material is placed on the lower belt whence it may be removed for sealing or further treatment. It will be noted that the device is so arranged that 105 both the upper and lower part of the belt are equally accessible to each operative and also equally accessible from each side of the table, and each serves as a conveyer moving oppositely to the other. The refuse culled out by 110 each operative is placed in the spout 12 if of solid form and if a liquid is allowed to escape

through the pipe 11, and is carried away by the conveyer in the trough 13.

What I claim is:

1. In a canning factory device, the combination of a table, a run-way above the table and spaced apart therefrom, a belt traversing the table and run-way in opposite directions, a series of receptacles in the table and adjacent to the edge of the belt, a trough beneath the table, drain pipes connecting the receptacles and the trough, a conveyer in the trough and spouts extending from openings in the table to the trough.
2. In a canning factory device, the combination of a table, a run-way above the table spaced apart therefrom and parallel therewith, a belt traversing the run-way in one direction and traversing the table beneath the run-way in the opposite direction, receptacles in the table adjacent to the edge of the belt, a trough beneath the table, a sprocket

chain in the trough, drag-bars on the chain and traversing the trough, drain pipes connecting the receptacles and the trough, and spouts extending from openings in the table to the trough.

3. A canning factory device comprising a belt arranged horizontally with going and returning parts superposed and spaced apart, a table near the lower part of the belt and supporting the same, and a run-way supporting the upper part of the belt and spaced apart from the table whereby both the going and returning parts of said belt are made accessible to be operated as going and returning conveyers.

In testimony whereof I affix my signature in presence of two witnesses.

WILLIAM S. THOMAS.

Witnesses:
